UNITED STATES PATENT OFFICE

HOWARD M. ZOERB AND RUDOLPH W. BUETTNER, OF MILWAUKEE, WISCONSIN, AS
SIGNORS TO NORDBERG MANUFACTURING COMPANY, OF MILWAUKEE, WISCONSIN,
A CORPORATION OF WISCONSIN

FELTING MACHINE

Application filed April 13, 1928. Serial No. 269,824.

This invention relates to machines for producing felt or felt-like sheets. Sheets of felt-like material made primarily of cow hair are quite extensively used as underlays for 5 rugs and carpets, and other purposes where a relatively inexpensive padding material of reasonably good mechanical strength is required.

The invention resides in certain improvements in machines for manufacturing such felts. Such machines as heretofore constructed included two plates between which the material to be treated is received, said plates being urged yieldingly toward each 15 other to compress the material and at the same time reciprocated relatively to each other in a direction at right angles to the line of pressure. The effect is to compact the hairs and rub them together, thus developing 20 as fully as possible the rather poor felting properties of the cow hair and similar materials customarily used.

Ordinarily these machines make use of a fixed horizontal supporting plate and a reciprocating overlying plate which compresses the material by its own weight. In the operation it is desired to change the amplitude of reciprocating motion to meet certain contingencies incurred in the manufacturing 30 process. One of the features of the present invention is the provision of means for changing such amplitude of motion conveniently and accurately.

Another feature of the invention is the provision of means for heating both plates while the relative reciprocation is taking place.

Other features of novelty will appear from the detailed description to be given of the preferred embodiment of the invention illustrated in the accompanying drawings, in which,—

Fig. 1 is a side elevation of the machine showing the plates separated to receive raw material.

Fig. 2 is an end view of the machine shown in Fig. 1, this view being on a slightly reduced scale and looking at the machine from the left relatively to Fig. 1.

Fig. 3 is a plan view of the machine.

Fig. 4 is a view of a portion of the main

driving shaft of the machine showing one of the adjustable eccentrics in detail.

Fig. 5 is a view of one of the adjustable eccentrics removed from the shaft and viewed from the right relatively to Fig. 4. 55

Fig. 6 is a similar view looking from the left relatively to Fig. 4.

Supported on a suitable foundation are two beam-like frame members 11 and 12, upon which is directly supported the lower 60 plate 13. This is a cored casting having internal water chambers 14 (see Fig. 1) the water being heated by steam as hereinafter described. The supply connection appears at 16. 65

Attached to the frame members 11 and 12 respectively, are air lift cylinders 17, of any ordinary form, having pistons connected to piston rods 18. Each rod carries at its upper end a yoke 19 having rollers 21. These 70 rollers 21 coact with the lower faces of brackets 22 bolted to the opposite ends of the upper plate 23. The upper plate 23 is also a cored casting having an internal steam chamber 24. A steam supply connection 25 is 75 connected at two points, 26, with the chamber 24, and leading from one end of the chamber 24 is a combined steam and condensate drain connection 27 which communicates by way of flexible hose 28 and pipe 29 with the inlet 80 connection 16 of the lower plate. Leading from the upper portion of the chamber 14 is a water discharge connection 31 which leads to a hot well or the equivalent. A stand pipe 33 open at its upper end is used to vent air 85 from the system.

The lift cylinders 17 are used to raise and lower the plate 23 relatively to the plate 13. Bolted to the beam member 11 and also resting on the foundation, are four frames 34, 90 identical with each other and each formed with seats to receive substantial bearing brasses 35 which are retained by removable caps 36. These bearing brasses are alined and support the main drive shaft 37 of the 95 machine. This shaft is rotated by a belt which runs on the pulley 38 fast on the shaft.

The frames 34 are arranged in pairs, the frames of each pair being relatively close to each other so as to support the shaft on each 100

side of an adjustable eccentric. This double support for the shaft is advisable because of the substantial mass of the plate 23 and the heavy stresses imparted to the shaft each time the direction of motion of the plate is changed.

Between the frames of each pair the shaft 37 is formed (see Fig. 1) with an eccentric circular portion 41. In order to secure satisfactory strength this portion 41 is preferably larger in diameter than the shaft and is preferably integral with the shaft. Swiveled on the eccentric portion 41 is an eccentric annulus 42. By the term "eccentric annulus" we mean to bring out the fact that the internal surface of the member 42, indicated at 43, is eccentric relatively to the external bearing surface 44 of the member 42. It follows that the eccentricity of the bearing surface 44, relatively to the axis of the shaft 37, may be varied or adjusted by rotating the member 42 on the eccentric portion 41 of the shaft.

At one side of the eccentric portion 41 the shaft 37 is formed with an integral collar 45 against which one face of the eccentric annulus 42 seats. This face is formed with a series of spaced tapered holes 46, the centers of these holes being in a circle eccentric with the internal surface 43.

Mounted in the flange 45 and slidable in a direction parallel with the axis of the shaft 37, is a stop pin or indexing pin 47 having a tapered head 48 which when projected by a spring 49 enters and fits closely in one of the holes 46, thus latching the annulus 42 in a definite angular relation to the shaft 37. The member 48 is retractable by a knob 51 and is used merely to secure accurate initial positioning of the annulus 42. When so positioned it is locked to the shaft 37 by a collar extension 52 formed integrally with the annulus 42 and split diametrically as indicated at 53. This split permits the collar to be deformed and clamped tightly upon a portion of the eccentric part 41 of the shaft 37 by means of heavy bolts 54 provided for that purpose. The split collar 52 is formed with two diametrically opposed bosses 55 which are bored at 56 to receive a bar which is temporarily inserted merely to turn the annulus 42 on the eccentric portion 41. To make this adjustment the bolts 54 are, of course, loosened and the tapered bolt 48 is withdrawn.

The purpose of the bolt 48 is not to carry any load, but is merely to insure accurate positioning of the annulus 42 at the time the bolts 54 are tightened. This accurate positioning is necessary because two eccentrics are used, and unless the eccentricity of the two be made identical in the various concurrent adjustment serious wear is inevitable. To accomplish this result the two eccentric structures are counterparts, the angular

spacing of the holes 46 being the same on both of the annuli 42 and the location of the tapered bolt 48 being the same on the two collars 45.

Running on the outer bearing surface 44 of each of the annuli 42 is a corresponding eccentric strap 57 whose rod 58 is pivoted at 59 to lugs 61 fast on the upper side of the upper plate 23.

To stop the rotation of the shaft 37 there is provided a brake drum 62 with which there coacts a brake band 63 which may be contracted into braking engagement with the drum by depressing a pedal 64. The pedal 64 is connected to contract the brake band 63 by a linkage of ordinary form, part of which appears at 65.

In operating the machine steam is supplied to the upper plate. Here part of the steam condenses, the remainder, with condensate, passing to the lower plate. The connections of the lower plate are such as to retain the lower plate full of condensate which is kept hot by such steam as passes from the upper plate. This is a simple and effective way of keeping the heating jackets free of air. In this way effective use of the available heat of the steam is secured, and a good transfer of heat to the plates is maintained.

The lift cylinders 17 are operated to lift the upper plate 23, the layer of material to be felted is placed on the plate 13, after which the air lifts 17 are operated to lower the upper plate upon the material. Rotation of the shaft 37 causes the plate 23 to reciprocate in a horizontal direction while resting upon the material, and the effect is to compact and felt the material into a sheet having the desired mechanical properties.

On the completion of the operation the air lifts lift the plate 23 so that the finished sheet may be removed. If at any time it is desired to change the amplitude of reciprocation of the plate 23, the bolts 54 on both eccentrics are loosened, the bolt 47 is retracted and the two eccentric annuli 42 are rotated simultaneously and by the same amount to the desired new position, in which they are again positioned by their respective bolts 48. While so positioned the annuli are clamped in fixed relation upon the shaft 37 by setting up the nuts on the bolts 54.

The device is of simple and rugged construction. The eccentrics may be easily adjusted and when adjusted maintain their adjustment indefinitely. The heating of both plates during treatment of the material results in a better product than can otherwise be secured.

Obviously various changes in the details of construction may be made and we do not mean to limit ourselves except to the extent specified in the claims.

What is claimed is:—

1. In a machine of the class described, the

combination of a pair of substantially horizontal plates, each having a heating jacket, one plate supporting the material to be treated and the other overlying and compressing the same; means for supplying steam to the jacket of the upper plate; connections for draining condensate from the jacket of the upper plate and conducting the same with uncondensed steam to the jacket of the lower plate; means for maintaining the last named jacket substantially full of condensate and for draining away excess condensate; and means for producing relative reciprocating motion between said plates in a horizontal direction.

2. In a machine of the class described, the combination of a pair of substantially horizontal plates, each having a heating jacket, one plate supporting the material to be treated and the other overlying and compressing the same; means for feeding steam to the jacket of the upper plate; means for maintaining the jacket of the lower plate filled with water; means for maintaining said water in a heated condition by waste heat from the upper plate; and means for producing relative reciprocating motion between said plates.

3. In a machine of the class described, the combination of a pair of plates having opposed faces between which the material to be treated is received, and provided with heating jackets substantially coextensive with said opposed faces; means urging said plates toward each other; means for producing relative reciprocation of the plates in a direction parallel with their opposed faces; means for feeding steam to one of said jackets; a connection between said jackets; and a discharge connection for the second jacket arranged to maintain said second jacket substantially full of condensate.

In testimony whereof we have signed our names to this specification.

RUDOLPH W. BUETTNER.
HOWARD M. ZOERB.
